UNITED STATES PATENT OFFICE.

SAMUEL A. LERNER, OF JERSEY CITY, NEW JERSEY.

DESIGN FOR A STORE-FRONT.

56,930.

Specification for Design.

Patented Jan. 18, 1921.

Application filed August 5, 1919. Serial No. 315,549. Term of patent 14 years.

To all whom it may concern:

Be it known that I, SAMUEL A. LERNER, a citizen of the United States, residing at Jersey City, Hudson county, in the State of New Jersey, have invented a new, original, and ornamental Design for a Store-Front, of which the following is a specification, reference being had to the accompanying drawing, forming part thereof.

In said drawing,

Fig. 2 is a vertical section taken on the line 2—2 of Fig. 1, and

Fig. 3 is a horizontal section taken on the line 3—3 of Fig. 1.

I claim:

The ornamental design for a store-front, as shown.

SAMUEL A. LERNER.
